UNITED STATES PATENT OFFICE

CARL P. BERGSTROM, OF MILLBURY, MASSACHUSETTS, AND CARL J. LINDEGREN, OF PROVIDENCE, RHODE ISLAND, ASSIGNEES TO CROMPTON & KNOWLES LOOM WORKS, OF WORCESTER, MASSACHUSETTS, A CORPORATION OF MASSACHUSETTS

MOUNTING FOR LOOM PICKING SPINDLES

Application filed January 15, 1929. Serial No. 332,692.

This invention relates to mounting for the picking spindle of a loom and it is the general object of the invention to provide means for varying the position of the spindle relatively to the shuttle box of the loom.

In some forms of weft replenishing looms the shuttle is actuated by a picker which slides along a spindle or picker rod mounted behind the shuttle. The picker stick is located behind the shuttle also so as to provide a clear path for the passage of an exhausted bobbin at the time of transfer. The picker spindle is ordinarily substantially parallel to the reed, but due to slight deformation of the lay, especially at the box end, the spindle will occasionally change its proper relation with respect to the reed so as to cause the picker to move in an improper path. It is an important object of our present invention to provide means for adjusting the outer end of the spindle so that the same may be kept in correct alignment with the reed.

It is a more specific object of our present invention to provide a holder for the picker spindle through which the latter extends freely, the holder being adjusted toward and from the shuttle box and being capable of limited vertical adjustment.

With these and other objects in view which will appear as the description proceeds, our invention resides in the combination and arrangement of parts hereinafter described and set forth in the claims.

In the accompanying drawing wherein a convenient embodiment of our invention is set forth,

Fig. 1 is a top plan view of a loom having our invention applied thereto, certain parts being removed for the sake of clearness,

Fig. 2 is a rear elevation taken in the direction of arrow 2, Fig. 1, and

Fig. 3 is an enlarged vertical section on line 3—3 of Fig. 2.

Referring particularly to Figs. 1 and 2 we have shown the loom lay L having a shuttle box 10 in which is mounted a shuttle S. The lay is provided with the lay end 11 having ears 12 to receive lay driving mechanism not shown. The lay end is pro-

vided with a boss 13 which receives the inner end of a picker spindle P. A check nut 14 mounted on the threaded end 15 of the picker spindle may serve to hold the picker spindle in fixed relation with respect to the boss, said picker spindle being threaded into the latter. The reed indicated at R in Fig. 1 is as usual positioned to engage the rear wall of the shuttle S and the latter is guided by the upright wall 16 of the box 10.

The picker stick 17 may be actuated in the usual manner and passes through a slot 18 in a picker 19 which is slidable on the rod P, having its forward end 20 in engagement with the outer end of the shuttle S. As the picker moves along the rod the shuttle is expelled from the box to move along the reed R. The matter thus far described is of common construction and is found not only on the drop box end of fancy looms, but also on the magazine end of certain weft replenishing looms.

Our invention relates more particularly to the means for adjusting the outer right hand end as viewed in Fig. 1 of the picker spindle P, and in carrying our invention into effect as shown more particularly in Fig. 3 we provide a carrier 30 preferably of cylindrical form as suggested in Fig. 1 and drill therethrough a hole 31 of proper size to receive the outer end of the picker spindle. The hole is not quite centrally located along the length of the carrier 30, but as shown herein is a little nearer the bottom than the top of said carrier for a purpose to be described hereinafter. The upper end of the carrier has a threaded hole 32 extending axially therethrough to receive a screw 33 having a head 34. The screw extends through an eye member 35 having a threaded shank 36 which extends into a threaded hole 36' located in a portion of the lay end 11. A check nut 37 holds the eye member 35 in fixed adjusted relation with respect to the lay end.

The bottom of the carrier 30 is provided with a threaded hole 38 similar to the hole 32 to receive a screw 39 having a head 40 which bears against an eye member 41 similar to eye 35. Said eye member 41 is pro-

vided with threaded shank 42 extending into a threaded hole 42' in the lay end and held tightly with respect to the latter by a check nut 43.

5. If desired we may employ a bracing screw 44 which is threaded into the carrier 30 and has a head 45 to engage the lay end 11. This screw 44 is held in position by a lock ~~nut 46~~ and may lie opposite the spindle P as shown in Fig. 3.

10. Under normal conditions the carrier 30 will be clamped against the eye members 35 and 41 by the upper and lower screws 38 and 39, respectively, thus holding said carrier in fixed position with respect to the lay, the distance of the outer end of the picker spindle P from the box back 16 being determined by the position of the screws 36 and 42 with respect to the lay end 11. If during the course of the operation of the loom it should be found that the outer end of the picker spindle moves too far forwardly, the screws 34 and 40 may be removed and the carrier 30 taken from between the eye members 35 and 41, after which the latter may be rotated to move rearwardly with respect to the lay end the proper distance. The carrier may then be inserted between the eyes and the screws 33 and 39 be replaced, a corresponding adjustment being made on screw 44 so that the latter will serve to brace the central part of the carrier with respect to the lay end. The opposite adjustment of course may be made if it is found that the picker spindle is too far to the rear of its proper position.

15. Should it be desired to effect a slight vertical adjustment of the outer end of the rod P the holder 30 may be inverted. The adjustment will be effected due to the previously described relation between the ends of the carrier and the hole 31, namely, that said hole is not exactly in the longitudinal center of the carrier.

20. From the foregoing it will be seen that we have provided a simple form of mounting for the outer end of the picker spindle, said mounting providing means for adjusting the position of the picker spindle toward and from the box back. It will also be seen that the screw 44 acts as a brace to steady the carrier 30 with respect to the lay end. It will furthermore be seen that by inverting the carrier a slight vertical adjustment of the hole 31 may be effected.

25. Having thus described our invention it will be seen that changes and modifications may be made therein by those skilled in the art without departing from the spirit and scope of the invention and we do not wish to be limited to the details herein disclosed, but what we claim is:

1. In a loom lay having a picker spindle the forward end of which is positioned with respect to the lay, a carrier for the outer

end of the spindle through which the latter extends, a pair of screw members located one above and the other below the spindle and threaded into the lay, and connection between the screw members and the carrier to hold the latter in fixed position with respect to the lay.

2. In a loom lay having a picker spindle the forward end of which is positioned with respect to the lay, a carrier member having a bore therethrough to receive the spindle, a screw threaded into each end of the carrier, one screw being above and the other below the spindle, and a threaded member to cooperate with each screw and held to the carrier and having threaded engagement with the lay.

3. In a loom lay having a picker spindle the forward end of which is positioned with respect to the lay, a carrier for the outer end of the spindle through which the spindle extends, a pair of spaced screw eye members threaded into and adjustable with respect to the lay, and means extending through the screw eyes and into and in holding engagement with the carrier to hold the latter fixed with respect to the screw eye members.

4. In a loom lay having a picker spindle the inner end of which is positioned with respect to the lay, a carrier for the outer end of the spindle through which the spindle extends, a pair of spaced screw eye members threaded into and adjustable with respect to the lay, and means extending through the screw eyes and into and in holding engagement with the carrier to hold the latter fixed with respect to the screw eyes, said means comprising a screw at each end of the carrier, each of the set screws extending through one of the eye members.

5. In a loom lay having a picker spindle the inner end of which is positioned with respect to the lay, a carrier having portions extending on opposite sides of the spindle and having an opening therein through which the spindle passes, means to hold the opposite ends of the carrier in fixed relation with respect to the lay, and a bracing means intermediate the ends of the carrier and interposed between the lay and said carrier to prevent vibration of the latter with respect to the lay.

6. In a loom lay having a picker spindle the inner end of which is positioned with respect to the lay, a carrier having an opening therethrough to receive the spindle, a pair of spaced parallel threaded members to extend into and be adjustable with respect to the lay, means to support the carrier with respect to the threaded members, and a bracing screw substantially parallel to the threaded members interposed between the carrier and the lay and to prevent vibration of the carrier.

7. In a loom lay having a picker spindle

the inner end of which is positioned with respect to the lay, a pair of spaced supports fixed with respect to the lay, a carrier to be supported by said supports in fixed relation with respect to the lay and having a 5 spindle receiving opening extending therethrough located nearer one end of said carrier than the other.

8. In a loom lay having a picker spindle the inner end of which is supported in fixed 10 position with respect to the lay, a threaded member extending into and capable of assuming a plurality of horizontal positions relatively to the lay, and a threaded spindle 15 supporting element operatively related to the member and capable of being held in a plurality of vertical positions relatively to the member.

In testimony whereof we have hereunto 20 affixed our signatures.

CARL P. BERGSTROM.
CARL J. LINDEGREN.
